UNITED STATES PATENT OFFICE.

THOMAS AUGUSTUS DRING, OF TROWBRIDGE, ENGLAND.

FLYING-MACHINE.

1,034,430.

Specification of Letters Patent.

Patented Aug. 6, 1912.

Application filed February 24, 1912. Serial No. 679,648.

To all whom it may concern:

Be it known that I, THOMAS AUGUSTUS DRING, a subject of the King of Great Britain and Ireland, and residing at "Sunny Bank," Trowbridge, in the county of Wilts, England, have invented new and useful Improvements in Flying-Machines, of which the following is a specification.

This invention relates to flying machines 10 of the type in which combined lifting and propelling devices are employed, each of which consists of a shaft carrying a plurality of flat radially arranged blades or vanes which spring from a common hub or center 15 and extend outward both longitudinally and radially at an angle with the axis of the shaft, so that during rotation both the inner and outer edges of said blades or vanes take an inverted cone-like path about their 20 axis of rotation, and it has for its object increasing the lifting and propelling power of the combined lifting and propelling devices whereby the efficiency and utility of the machine is materially enhanced.

According to the present invention the 25 blades or vanes are inclined in the direction of rotation, that is to say, their tip ends are in advance of their root ends; the outer edges of the blades or vanes are set at such 30 an angle with the axis of the shaft carrying them that the path formed by them when rotating has an angle of from 80° to 90°; and the units of each pair of devices employed are inclined outward from one another each at an angle of from 40° to 45° 35 to the vertical. Means are also provided to prevent the inflow of air at the bases or roots of the blades or vanes so as to leave undisturbed the inflow of air at the base of 40 the coned path formed by the tips of the blades and the outflow of air at the sides of the coned path formed by the outer edges of the blades.

In order that this invention may be fully 45 understood I will describe it with reference to the accompanying drawing in which:

Figure 1 is a view in side elevation, partly in section, of a machine embodying this invention. Fig. 2 is a view in plan thereof. 50 Fig. 3 is a view in section on line A—A of Fig. 1 and Figs. 4 and 5 are views in elevation and plan respectively on an enlarged scale—of the improved combined lifter and propeller.

Throughout the views similar parts are 55 marked with like letters of reference.

The combined lifter and propeller has a plurality of blades or vanes a^1 —that illustrated by Figs. 4 and 5 having three—which are inclined in the direction of rotation, 60 *i. e.*, with their tips a^4 in advance of their roots or bases a^5 . The hub which carries the blades or vanes is of such a size as will prevent any inflow of air at their roots or bases or alternatively—in order to save 65 weight—the hub may be provided with a shield, such as a , for said purpose. The inner edges a^2 of the blades are curved so that the path taken by them is that of a concavely curved cone, and the outer edges 70 a^3 are straight from the root to near the tip so that the path taken by them is that of a straight or flat-sided cone having an angle of from 80° to 90°.

In lifters constructed in the manner specified the air passes out from the path of the blades or vanes at approximately right angles to the outer edges of said blades, *i. e.*, at right angles to the path made by the outer edges of said blades, and therefore 80 at a considerable angle to the axis of the shaft carrying them. By using lifters of this type arranged in pairs with their two shafts a and a inclined outward from one another at such an angle that each lies at 85 an angle of from 40° to 45° to the vertical, and by causing said lifters to rotate in opposite directions the greatest possible action and reaction of and on the air are obtained and the body of the machine can be suitably 90 disposed in relation to the lifters without interfering with said action and reaction.

In the construction shown in Figs. 1, 2 and 3 the body of the machine—which is of any suitable construction and material—is 95 shown taking the form of a boat and is provided with two "vertex lifters", the arrangement being such that with the shafts of the lifter inclined upward at an acute angle and at a right angle with the longitudinal axis of the machine the latter will 100 be lifted. The shafts a of the lifters are driven by skew bevel gearing running in a metal gear case b . The driver wheel is carried on a short horizontal shaft, one end of 105 which projects from the gear case sufficiently to allow of its being coupled to the shaft of a suitable engine c . This connection may be

made through the medium of a clutch. The shafts of the two driven wheels project upward from the gear case *b* at angles of 45° or thereabout and revolve in opposite directions. Universal joints *d* of the ring and pin type are fixed to the ends of these shafts where they project and serve to connect them with the shafts *a* of the vortex lifters. At a suitable distance from such universal joints each vortex lifter shaft passes through a ball thrust bearing carried in a movable block *e* to which a certain amount of lateral motion can be imparted by means of a screw and nut *f* controlled by a rod and hand wheel *g*. The thrust of the shaft upon the movable plummer block is taken by a steel band *h* surrounding the base of the plummer block and securely fastened thereto, and the other end of the band encircles a fixed circular block *k* around which it is free to move within certain limits, and which is bolted to the framework *m* immediately below the universal joint, the center of the block coinciding with the central pivot of the joint. The band thus acts as a radius rod describing the same arc as the shaft immediately above it. From this fixed block radiate tension rods (not shown) to different parts of the framework supporting the aviator and machinery. The whole lifting and propelling power of the vortex lifters is thus concentrated upon these two blocks. For rising vertically and for hovering in the air each vortex lifter shaft is brought into alignment with the geared shaft to which it is connected. For forward progression the two hand wheels *g* are turned simultaneously in opposite directions until the desired speed is attained, the right and left handed screws *f* to which they are connected conveying a forward lateral motion to the respective vortex lifter shafts through the two movable plummer blocks *e*. To travel backward the motion of the hand wheels is reversed, and to steer to the right or left both hand wheels are turned in the same direction, either clockwise or anti-clockwise. The effect of this latter action is to throw forward one lifter and to throw backward the other.

A fan-like expanding and contracting tail such as *t* may be employed to operate in conjunction with the vortex lifters when they

are at rest to insure the safe descent of the machine in case the motor stops or any accident occurs to the machinery.

What I claim and desire to secure by Letters Patent is:

1. In a flying machine, a combined lifting and propelling device consisting of a shaft adapted to be rotated, and a plurality of radially arranged flat blades or vanes mounted on a common hub on said shaft and inclined in their direction of rotation, the inner edges of said blades being convexly curved so that when rotating the path formed by them is that of an inverted cone with concavely curved sides and the outer edges of the blades being straight from the root to near the tip so that the path formed by them when rotating is that of an inverted cone with straight sides.

2. In a flying machine, a combined lifting and propelling device consisting of a shaft adapted to be rotated, a plurality of radially arranged flat blades or vanes mounted on a common hub on said shaft and inclined in their direction of rotation, the inner edges of said blades being convexly curved so that when rotating the path formed by them is that of an inverted cone with concavely curved sides and the outer edges of the blades being straight from the root to near the tip so that the path formed by them when rotating is that of an inverted cone with straight sides, and means for preventing the inflow of air at the bases or roots of the blades.

3. In a flying machine the combination of two devices each consisting of a rotating shaft and a plurality of flat surface blades or vanes each radially arranged relative to the axis of said shaft carrying them and each inclined in the direction of rotation, the inner edges of said blades or vanes being of convex shape and the outer edges of flat shape so that on rotation said edges form inverted cone like paths, means for imparting motion to said shafts, and means for varying the angles of said shafts simultaneously both in the same and in opposite directions.

THOMAS AUGUSTUS DRING.
